(57) **CLAIM**

The ornamental design for an integrated underwater waist propeller as shown and described.

DESCRIPTION

- 1.1 Front, top, right side perspective
1.2 Back, top, right side perspective
1.3 Back, top, right side perspective, in a second configuration
1.4 Back, top perspective, in a third configuration
1.5 Front
1.6 Back
1.7 Right
1.8 Left
1.9 Top
1.10 Bottom

A new, original and ornamental design for an integrated underwater waist propeller, of which the following is a specification, reference being made to the accompanying drawings forming a part thereof, and of which the following is a description: FIG. 1.1 is a front, top, right side perspective view of an integrated underwater waist propeller showing our new design; FIG. 1.2 is a back, top, right side perspective view thereof; FIG. 1.3 is a back, top, right side perspective view thereof in a second configuration; FIG. 1.4 is a back, top perspective view thereof in a third configuration; FIG. 1.5 is a front elevational view thereof; FIG. 1.6 is a back elevational view thereof; FIG. 1.7 is a right side elevational view thereof; FIG. 1.8 is a left side elevational view thereof; FIG. 1.9 is a top plan view thereof; and FIG. 1.10 is a bottom plan view thereof; the broken lines depict portions of the integrated underwater waist propeller which form no part of the claimed design.

1 Claim, 10 Drawing Sheets

Front, right, top perspective
